ADDRESSING MACHINE

Harmon P. Elliott, Watertown, Mass.

Application April 13, 1932, Serial No. 604,985

38 Claims. (Cl. 101—48)

This invention relates to stencil printing or addressing machines.

One of the objects of the present invention is an improved machine for automatically addressing envelopes.

In an envelope addressing machine of the character of the present invention the stencils or address bearing devices are moved from a holder through printing position and fall into a receiver. The envelopes are moved from a holder into and out of printing position and fall into a receiver. The location of the stencil and envelope holders and receivers is a matter of considerable importance in providing a well appearing machine having simple and accessible parts and arranged wherein the printing operation can be watched; and in the present invention the stencil and envelope holders are arranged at opposite ends of the machine while the stencil and envelope receivers are located at the opposite sides of the machine, with the stencils and envelopes moving in the opposite direction into a common printing position and thence moving at right angles to their previous line of movement into their respective receivers. Such an arrangement constitutes a further object of the invention.

It is quite common to utilize only a portion of the total number of addresses of a stencil collection and it is an object of the present invention to provide improved mechanism for effecting the printing of selected addresses only on the envelopes and to move envelopes into printing position only in accordance with selected stencils.

The operation of the printing mechanism is controlled by selector mechanism governed by the stencils, the stencils controlling the completion of an electric circuit that governs the selector mechanism. For some purposes it is desirable to effect the operation of the printing mechanism when the electric circuit is made by the stencil and at other times to interrupt the printing operation when the circuit is interrupted by the stencil. It is an object of the present invention to provide a selector mechanism which not only controls the operation of the printing mechanism but also of the envelope feeding mechanism and that can be conditioned readily to operate as desired under both conditions.

A further object is generally to improve the construction and operation of addressing machines.

Fig. 1 is a front elevation of an addressing machine embodying the present invention.

Fig. 2 is a plan view of the essential elements of the machine of Fig. 1.

Fig. 3 is a section taken along line 3—3 of Fig. 2.

Fig. 4 is an enlarged front elevation illustrating in detail the envelope feeding mechanism.

Fig. 5 is a section taken along the line 5—5 of Fig. 2, and illustrating the envelope feeding mechanism.

Fig. 6 is a section taken along line 6—6 of Fig. 5, and illustrating particularly the envelope feeding drum.

Fig. 7 is a sectional elevation taken along line 7—7 of Fig. 2, and illustrating mechanism for moving the used stencils toward the stencil receiver.

Fig. 8 is a detail of the stencil engaging mechanism of Fig. 7, but in stencil free position thereof.

Fig. 9 is a perspective detail of the stencil track construction at the junction of the angularly related sections of the track.

Fig. 10 is a perspective detail of the stencil moving member of Figs. 7 and 8.

Fig. 11 is an end view and Fig. 12 is a side view of the electromagnet mechanism that controls the operation of the envelope feeding drum.

Fig. 13 is a circuit diagram of the electromagnets that control the operation of the selector mechanism and the envelope feed drum.

Fig. 14 is a front elevation of the control magnet for the selector mechanism.

Fig. 15 is a plan detail of the cam actuated lever system for operating the envelope ejecting rolls.

Fig. 16 is a side elevation of the carriage envelope ejecting rolls.

Fig. 17 is a perspective view of a stencil that can be employed in connection with the present invention.

The machine embodying the present invention comprises a horizontal table 20 supported at the top of a base or frame 22. A holder 24 for a vertical stack of stencils 26 is located at one end of said table and extends upwardly thereabove.

The successive lowermost stencils of the stack are moved from the stack by means of a reciprocating pusher 28 of more or less usual construction and operated in more or less the usual manner

into and along the rails 30 and 32 of a track which extends horizontally in spaced relation above the table toward the other end thereof and connects with other and right angularly disposed rails 30a

and 32a which extend to the rear of the machine and guide the stencils into a position where they

5

55

fall from the rails of the track into a stencil receiver 34 located beneath the track. The stencils are or may be rectangular in shape, as illustrated in Fig. 17, and are moved in the direction 5 of their length along the rails 30 and 32 into and out of a printing position and thence in the direction of their width along the rails 30a and 32a into the stencil receiver.

The pusher 28 is reciprocated to move the 10 stencils from the holder into the track by means of a link 36 which is located under the table 20 and is pivoted at one end to the pusher and at the other end to an arm 38 of a vertical hub 40 which is oscillable on a vertical stud 42, see 15 Figs. 1 and 3. Said hub 40 has a laterally extended arm 44 that is located in a cam slot 46 formed in the upper extension of an arm 48 that is pivoted to a bracket 50 secured to the table 20. The shape of the cam groove is such that when 20 said arm 48 is moved from a raised position into the lowered position shown in Fig. 3, a stencil is caused to be moved from the holder into and along the track. The arm 48 is actuated in more or less the usual manner by a reciprocating connecting rod 52 from a power mechanism 54 that is now well known in the art, which mechanism has a shaft 56 that is driven continuously by means including the pulley 58.

The stencils are advanced in a step by step 30 manner through the printing position and thence into the wide portion of the stencil track or into the rails 30a, 32a. Separate mechanism is employed to move the stencils in a step by step manner along the wide portion of the track and into 35 the stencil receiver. Said mechanism, illustrated more particularly in Figs. 2 and 7 through 10, includes a reciprocating slide 60 which is horizontally slidable in a stationary guide member 62 that is disposed above the rail 30a. Said slide 40 carries a bracket 64 which extends over the wide portion of the track and has a shaft 66 journaled therein that supports a finger frame 68 having forwardly directed fingers 70. Said frame can be lowered into position to engage the forward wide 45 edge of the stencil and thereby move the stencil rearwardly along the wide track. The finger frame can also be moved to an elevated position to be free from engagement with the stencils at the time the slide 60 moves forwardly. It will be 50 understood that in the present machine a stencil is advanced along the track at each cycle of operation of the machine and hence the fingers 70 are adapted to be in lowered position and to engage a stencil and move the stencil rearwardly 55 at each rearward stroke of the finger frame. The finger frame has a rearwardly extended arm 72 that is connected with a tensile spring 74 that tends to rotate the arm in a counterclockwise direction to bring the fingers 70 in a lowered 60 position to engage the stencils. The fingers 70 are raised and lowered by means including a bar 76 which is extended horizontally over the frame parallel with the wide portion of the stencil track. The finger frame has an upwardly extended arm 65 78 that carries a roller 80 that rides upon the upper face of said bar. Said bar is secured to a frame 82, see especially Figs. 2 and 4, that is horizontally pivoted to a bracket 84 fixed to the left hand portion of the table. The bracket is 70 raised and lowered in timed relation to the movement of stencils, not only for the purpose of controlling the positions of the fingers 70 but also for effecting the positioning of the envelopes into printing position, as will presently appear, 75 by means including a shaft 86, see Figs. 1, 2, 4 and

5. Said shaft is journaled in brackets 88 and 90 beneath and transversely of the table and is rotated in timed relation to the stencil movements. Said shaft at its forward end is provided with a cam 92 which engages a roller 94 of an arm 96 that is secured to the frame 82. The shape of the cam and its relation with the roller 94 is such that it causes said frame 82 and consequently the bar 76 to be lowered at the time the fingers 70 are above and forward of the front edge of the stencil. The slide 60 that reciprocates the fingers 70 is also reciprocated in timed relation to the stencil movement in such manner as to bring the fingers into position in front of the successive stencils in the wide portion of the track 15 at the time the line of stencils in the narrow portion of the track is stationary and to move the stencils out of the line of movement of the stencils in the narrow portion of the track before said stencils are advanced. This movement of the 20 stencils in the wide portion of the track is carried out at the time an envelope is being moved into printing position.

The reciprocating mechanism for the slide 60 includes a link 98 which is pivoted at its front end to the slide and at its rear end to the upper end of a lever 100, which extends downwardly over the left hand end of the table and is pivoted on a pin 102 to the frame 22. The lower end of the lever is connected by means of a connecting 30 rod 104 to a crank arm 106 fixed to a shaft 108. Said shaft is journaled in an arm 110 of the aforesaid bracket 90 at right angles to the shaft 86 and drives said shaft by means of the miter gears 112. The shaft 108 is driven through a 35 sprocket 114 and a chain 116, see especially Figs. 1 and 5, from a shaft 118 which is connected through reduction gearing 120 with the shaft 56. The arrangement is such that the shafts 86 and 108 make one complete revolution for each cycle 40 of operation of the machine.

Stencil printing mechanism is located at the printing position and is illustrated particularly in Figs. 1, 2 and 3. Said mechanism includes a printing roll 122 which is rotatably mounted between the forked arms 124 of a bell crank lever 126 that is pivoted on a shaft 128 carried by the bracket 50. Said bell crank lever has a downwardly depending arm 130 that is pivotally connected through a link 132 to an arm 134 that is pivoted at 136 to the bracket 50 concentrically with the actuating arm 48. A platen 138 is carried by a pivoted frame 140 beneath the printing roll 122 and the stencil track and is movable upwardly to hold an envelope disposed beneath the track into position to be engaged by a stencil therein. The platen is reciprocated by a cam arm 142 which is fixed to the arm 134. The arrangement is such that when said arm 138 is moved upwards in a counterclockwise direction, the 50 platen and printing roll 122 are moved toward each other.

The arm 134 is at times adapted to be connected with and at other times disconnected from the actuating arm 48 depending upon whether or not it is desired to print from the stencil that is the next to be moved into printing position. To this end the arm 134 has a latch member 144 pivoted thereto and extended upwardly thereabove. The latch member has a detent 146 that is adapted to 70 enter a recess 148 of the arm 48 whereby to establish an operative connection between said arms 48 and 134. A spring 150 serves to urge the latch member 144 into position for engagement with the arm 48. Selector mechanism presently to be de- 75

scribed is provided to control the position of the latch and to determine whether or not the printing mechanism is to be reciprocated after certain stencils have been moved into printing position. 5 The printing roll 122 is supplied with ink in more or less the usual manner by mechanism 151 not herein necessary to describe.

The envelopes that are adapted to be addressed by the present machine are contained in a vertical stack 153, see Fig. 1, in an envelope holder 154. Said envelope holder is disposed at the left hand end of the table in line with the narrow portion of the stencil track and comprises an upstanding front plate 156 and an opposed upstanding rear plate 158. The front plate 156 is provided with a horizontal ear 160 at the bottom thereof which slides upon a ledge 162 of the table so that the plate can be moved forwardly and backwardly to adjust the holder for various sizes of envelopes. 10 The rear plate 158 is similarly provided with a horizontal ear 164 that overlies and rides upon the ear 160. The ears are longitudinally slotted and a screw 166 passes through the slots in said ears and into the ledge 162 whereby to secure the plates 15 25 releasably in adjusted position. A horizontal rod 168 extends loosely through the side plates above the bottom thereof and is adapted to support the stack of envelopes in an inclined position so that the front edges thereof are against a vertical 30 guide plate 170. Said plates 156 and 158 are provided with parallel forward extensions 172 and 174 which constitute tracks along which the envelope is guided into printing position, the track 174 being behind the printing roll and being 35 longer than the track 172. The envelopes are moved into printing position and against an adjustable stop member 176. Said stop member has an arm 178 loosely pivoted thereto at the rear end and adapted to bear by its weight against 40 the successive envelopes as they are being moved forwardly out of printing position for the purpose of preventing the edge of the envelope that is adjacent the stop from moving upwardly as the envelope is ejected. The forward edge of the stack 45 of envelopes rests upon a feed roll 180, see more particularly Figs. 1, 2, 4, 5 and 6. Said feed roll is loosely mounted upon the shaft 86 and the upper portion of its periphery extends through an opening in the table 20 and into the lower portion 50 of the envelope holder. A portion of the periphery of the feed roll or drum is occupied by a pair of opposed corrugated rubber bands 182 which are secured to the drum at the opposite edges thereof. The remaining peripheral portion 55 of the drum is smooth and is adapted to pass under the stack without withdrawing envelopes therefrom. The rubber bands when engaged with the stack of envelopes has sufficient frictional engagement therewith to move the successive lowermost envelopes out of the stack and toward the printing position. The envelope feed drum is adapted to be stationary at the time a stencil is passed through the printing position without printing therefrom. Hence the drum is provided 60 with clutch mechanism for connecting it operatively with the driving shaft 86. The clutch mechanism includes a disc 184 that is fixed to the shaft 86 and has a notch 185 in its periphery. The drum 180 has a latch arm 188 pivoted on a pin 190 fixed to the web of the drum, the arm being urged by a spring 192 constantly toward engagement with the periphery of the disc 184. The latch arm has a detent 194 that can enter the notch 185 and thereby establish driving 65 connections between the drum and the shaft. When 70

the detent 194 is out of the notch the disc can rotate independently of the drum and the drum is held stationary by a brake member 196 that frictionally engages the periphery of the drum. The driving engagement between the arm 188 and the disc 184 is controlled by mechanism which in turn is governed by the stencils in such manner that a stencil which is to be passed through the printing position without being printed therefrom disengages the arm and disc so that the shaft 86 10 can rotate while the drum is stationary and hence to prevent the feeding of an envelope. Said mechanism includes a clutch tripping rod 198 which is horizontally slidable in the bracket 90 in one direction toward the drum to position its inner end between the disc 184 and the latch arm 188. In this position the rotation of the drum and the arm causes a cam portion 200 of the arm to ride over the end of the pin 198 and thereby move the latch arm outwardly to disengage it 15 from the driving disc 184, whereupon the feed drum becomes stationary. This stationary position of the drum is illustrated in Fig. 4, where the ends of the envelope driving bands 182 are just in position to engage the lowermost envelope 20 of the stack when the drum is again advanced. The rod 198 is slidable in the opposite direction out of position between the latch arm 188 and the disc 184 whereby to permit the latch arm to move inwardly so that the detent 194 rides upon the 25 periphery of the disc and ultimately drops into the notch 185 thereof to establish the driving connection between the disc and the drum.

The movements of the rod 198 are controlled, at will, by either one of independently operable 30 electromagnets 202 and 204 which are mounted upon a bracket 206 secured to the underside of the table at the rear portion thereof. An armature 208 overlies both electromagnets and is pivotally mounted in between them, the armature 35 being loose on a shaft 210 which is carried by a supporting structure 212. The armature has a bifurcated extension 214 at one end in which the notched portion 216 of the tripping rod 198 is loosely received. Movement of the armature in 40 a counterclockwise direction serves to move the rod 198 into a clutch disengaged position and movement of the rod in a clockwise direction 45 serves to move the tripping rod in the opposite direction whereby to effect the engagement of 50 the clutch mechanism.

It has been stated heretofore that the printing operation can be effected either when the stencil next to be moved into printing position permits the closing of a normally open control circuit, 55 or holds the control circuit open, as desired. One of the electromagnets, as the electromagnet 204, is arranged to establish connection between the driving shaft 86 and the envelope feed drum 180 when the control circuit is completed whereby to 60 permit the feeding of the envelope into printing position. The other electromagnet 202 is arranged to establish driving connections between the shaft and drum, and the consequent feeding of an envelope when the control circuit is open 65 and to break the driving connection and prevent the feeding of an envelope when the control circuit is closed. Mechanism is provided for the purpose of selecting whichever electromagnet is desired for operating the armature 214. Said 70 mechanism includes a hand operated arm 218 which is carried by the pivot shaft 210 and is located in a slot 220 of the armature. An over-center spring 222 is connected to the arm 218 to hold the arm either in the position shown in 75

Fig. 12, or in a similar position on the other side of the center of the shaft 210, as desired. The arm 218 in the position shown in Fig. 12 engages one side wall of the slot 220 so that the spring 222 holds the armature against the electromagnet 204 and away from the electromagnet 202. Hence when the electromagnet 202 is energized the armature is attracted thereto against the pull of the spring and consequently moves the tripping rod 198 in a position to disengage the clutch mechanism and prevent the feeding of an envelope. When the electromagnet 202 is unenergized the clutch mechanism is engaged and the envelope feed drum rotates continuously with its drive shaft 86 so that successive envelopes are fed out of the envelope holder, the feeding of envelopes being interrupted only at times when the electromagnet 202 is energized. When the arm 218 is in the opposite position the armature 208 is held against the electromagnet 202 and away from the electromagnet 204. In this position the tripping rod 198 normally holds the clutch disengaged and the clutch is engaged only when the electromagnet 204 is energized.

The successive envelopes are not moved completely into printing position by the feed drum 180 but only sufficiently toward the printing position to be engaged by a pair of feed rolls 224 and 226, see especially Figs. 1, 2 and 4, which are disposed close to and in front of the outer rail 30 of the narrow portion of the track, and which rolls advance the envelopes into the printing position. The lower feed roll 224 is an idler roll and is journaled in a bracket 228 that is secured to the underpart of the table and extends upwardly through an opening therein. The upper feed roll 226 is continuously driven and is fixed to a shaft 230 that is journaled in the aforesaid bracket 82. As has been previously described the bracket 82 is reciprocated in a vertical direction by the arm 96 and cam 92 for the purpose of controlling the movement of the stencils along the wide portion of the track. This reciprocatory movement of the frame 82 also moves the roll 226 toward and away from the idler roll 224 whereby to control the advancing of an envelope between said rolls. When said frame 82 is in a lowered position the roll 226 is in position to bear upon an envelope thereunder and to move the envelope into printing position. The movements of the frame 82 are so timed that envelopes are fed into printing position before the completion of the printing movement of the platen and printing roll. The feed roll 226 is adapted to have a greater peripheral speed than that of the feed drum 180 whereby to move the envelopes rapidly in printing position. The roll 226 is driven by suitable means as the chain 232 which is passed over a sprocket 234 fixed to the shaft 230. The chain passes over an idler pulley 236 and also over a slack take-up roll 238 journaled on a spring urged arm 240 and about a driving sprocket 242 that is fixed to a hub 244, see especially Fig. 5, that is loose on the shaft 86. The hub 244 has a pulley 246 fixed thereto which is driven by a belt 248 from a pulley 250 fixed to the shaft 56. The roll 226 need not rotate in any timed relation with other elements of the machine so that the chain 232 can be replaced by a belt or other driving means if desired.

After the printing operation has been effected the envelope that is disposed in printing position is adapted to be removed or ejected therefrom toward the front of the machine along a line parallel with the guiding edge of the stop member

176. The ejector mechanism, see especially Figs. 1, 2 and 4, comprises a pair of continuously rotating feed rolls 252 which are disposed in front of the printing roll 122 and are fixed to a drive shaft 254 journaled in brackets 256 carried by the front track 32. Said shaft 254 is rotated continuously by a belt 258 that is passed over a pulley 260 of said shaft and also over a pulley 262 of a jack shaft rotatably supported in the lower portion of the base of the machine and driven by a belt 264 from a second jack shaft 266 which in turn is driven through a belt 268 from the shaft 56 of the power mechanism. The continuously rotating rolls 252 cooperate with a pair of idler rolls 270 that are loosely journaled in upstanding arms 272 of a slide 280, which slide is vertically reciprocable in a bracket 282, see especially Figs. 4, 15 and 16. Movements of the slide are controlled by a lever system including an arm 284 which is fixed to the inner end of the shaft 286 journaled in arms 20 of the aforesaid bracket 228. Said arm 284 overlies the rear face of the slide 280 and has a longitudinally elongated slot 288 therein in which a roller 290 of the slide 280 is located so that reciprocatory movement of said arm 284 in a vertical direction causes the raising and lowering of the slide. A spring 292 is connected with said arm 284 and serves to maintain the slide 280 yielding in an elevated position or in cooperative relation with the continuously rotating driving rolls 252. An arm 294 is fixed to the front end of the shaft 286 and has a cam roller 296 thereon which is in engagement with a cam 298 fixed to the drive shaft 86. The cam is so arranged as to effect the raising and lowering of the slide 280 at suitable periods. When the roller 296 is opposite the depressed portion 300 of the cam the spring 292 urges the slide upwardly and thereby presses any envelope that may be thereabove against the feed rolls 252 so that the addressed envelope is ejected forwardly out of printing position and, if desired, into a suitable receptacle 302 that lies mainly below the table. The ejection of the addressed envelopes is timed to take place after the platen and printing roll have released the envelope and prior to the movement of a new envelope in a printing position.

It has been stated heretofore that selector mechanism controlled by the stencils is provided so that unwanted stencils, that are automatically located, can pass through the machine without being printed therefrom. Said selector mechanism is illustrated particularly in Figs. 1, 2, 3 and 14. Said mechanism includes a selector frame 304 which is disposed above and is reciprocable toward and away from the narrow portion of the track at one side of the printing position and is fixed to a shaft 306 journaled in a bracket 308 carried by and electrically insulated from the table. Said selector frame can carry one or more selector pins 310 which when the frame is lowered can make electrical contact with one or the other of the electrically grounded tracks 30, 32, if the stencils 26 have passages 312, see Fig. 17, therethrough that are aligned with one or more of the selector pins at the time the selector frame is moved downwardly. The arrangement can be such as to effect the printing of the stencil that permits a selector pin to move through a passage 312 and electrically engage the track; and it can also be such as to prevent the printing operation of the machine on the stencil that permits the electrical contact between a selector pin and the track. The selector mechanism, like the envelope feeding mechanism heretofore described, is ca-

pable of being operated in accordance with either system to control the operation of the printing mechanism. The selector frame 304 is reciprocated by a link 314 which is pivotally connected to, but is electrically insulated from, an upstanding arm 316 of the shaft 306. Said link is also pivotally connected at its rear end to an upstanding arm 318 of a shaft 320 which is journalled in a bracket 322 and has a depending arm 324 that extends through a passage in the table and terminates in a cam roller 326 that is disposed at one side of the upwardly extending projection 328 of the reciprocating arm 48, and is maintained in engagement with a cam face 330 of said arm. Said cam face is so arranged that, at the upper portion of the stroke of said arm 48, the arm 324 is permitted to move in a counterclockwise direction whereby to move the selector frame downwardly to feed the stencil therebeneath and thereby determine whether or not a printing operation shall be effected on such stencil. The selector mechanism includes a frame 332 which is pivoted at 334 to the bracket 322 and has a depending arm 336 provided with an extension 338 that overlies a roller 340 carried by the upper end of the latch arm 144, which arm as has been explained, controls the connection between the arm 48 and the printing mechanism. Said frame 332 is urged by a spring 342 for movement in a clockwise direction to permit the engagement of the latch arm 144 with the actuating arm 48. The frame 332 has an upwardly extended detent arm 344 that has opposed upper and lower detents 346 and 348 respectively that lie on opposite sides of a latch member 350. Said latch member 350 is carried reversibly by an arm 352 that is loose on the shaft 320. When the latch member 350 is in the position shown it is capable of engagement with the upper detent 346 and in such position conditions the mechanism to effect a printing operation on a stencil that does not permit contact to be made between a selector pin and the track. When the latch member 350 is inverted and is in position to engage the lower detent 348 the arrangement is such that a printing operation is effected on the stencil that permits contact to be made between a selector pin and the track. When the latch member is free from the upper detent 346 it can drop. The latch member is raised and lowered by means of a lever 354 which is pivoted intermediate its ends at 356 to the bracket 322 and one end of which lies beneath the latch member 350 and the other end of which carries an armature 358. Said armature is moved downwardly into attracted position by an electromagnet 360 whereby to elevate the latch 350; and the armature moves upwardly into released position by the weight of the other end of the lever. The electromagnet 360 is in the circuit of the track and the selector pins so that it is energized when connection is established between a pin and the track. The electromagnets 202 and 204 that control the operation of the envelope feeding mechanism can be connected in series with the selector pin circuit but preferably are controlled through a separate circuit by the energization of the electromagnet 360, which magnet acts as a relay for the circuit of the envelope feed control magnets. To this end the armature 358 carries an insulated movable contact member 362 which cooperates with the insulated stationary contact member 364 that is in the circuit of the aforesaid magnets. The circuit connections are illustrated in Fig. 13 and need not be explained in detail.

Current for actuating the electromagnets can be derived from any source as the transformer 366. A double throw switch 393 is provided for selectively and separately connecting the electromagnets 202 and 204 in their control circuit. The frame 332 is provided with a forwardly directed arm 370 that has a latch roller 372 thereon that cooperates with a cam face 374 of the actuating arm 48. When said arm is moving upwardly the cam face 374 causes the frame 332 to move in a counterclockwise direction so that the detent 346 is disengaged from the latch member 350 which then can drop if the electromagnet 360 is not energized. If this is the case, when the arm 48 moves downwardly so that the cam 374 moves away from the roller 372 the spring 342 will then move the frame in a clockwise direction away from the latch arm 144 so that said latch arm can engage the actuating arm 48, and, on the next upward stroke of said arm, effect the printing operation. The cam 374 rotates the frame 332 in a counterclockwise direction, or into a position where the latch member 144 is disengaged, at each upward stroke of the arm 48, and the latch member 350 in the electromagnet determines whether or not the frame will be held in such position to hold the latch member 144 out of engagement. The arrangement between the cams 330 and 374 is such that the selector frame is in lowered position and hence a contact is made if one is to be made and the electromagnet 360 is energized at the time the cam 374 is passing out from under the roller 372 and permitting the frame 332 to move in a clockwise direction. If the circuit is closed and the magnet is energized at this time the detent 346 comes up against the projection of the raised latch 350 so that the frame 332 is held from counterclockwise rotation and at the same time the detent 346 holds the latch from dropping. Hence the frame 332 is in position to hold the latch member 144 out of engaged position and thus prevent a printing operation. If, however, no circuit is made through the stencil the electromagnet 360 will not be energized and the latch member 350 will not be raised and hence the frame 332 is free to move in a clockwise direction and permit the engagement of the latch member 144 and thereby effect the printing operation. When the latch member 350 is inverted so that it engages the detent 348 the arrangement is such that a printing operation is effected when the control circuit through the stencil is completed. Under these conditions when the selector frame is lowered and a selector pin 316 passes through a passage 312 of the stencil the electromagnet 360 becomes energized and raises the latch member from engagement of the detent 348 so that the frame 332 is free to move in a counterclockwise direction and permit a printing operation subsequently to take place. If the electromagnet 360 is not energized the latch member 350 remains in engagement with the detent 348 so that no printing operation takes place.

I claim:

1. A stencil printing machine comprising reciprocating printing mechanism operative on stationary stencils and envelopes, guiding and advancing means for advancing successive stencils into the action of said printing mechanism, guiding and advancing means operative between periods of operation of said printing mechanism to advance successive envelopes independently of the stencils in one direction into the action of said printing mechanism and to leave the en-

velopes stationary for the action of said printing mechanism, and other means also operative between the periods of operation of said printing mechanism to advance successive addressed envelopes in another direction out and away from the action of said printing mechanism.

5 2. A stencil printing machine comprising printing mechanism, advancing and guiding means for advancing successive unused stencils in one direction toward said printing mechanism, guiding and advancing means for advancing the used stencils in another direction away from said printing mechanism, and guiding and advancing means to advance successive unaddressed envelopes in one direction toward said printing mechanism and other means to advance the addressed envelopes in another direction away from said printing mechanism.

10 3. A stencil printing machine comprising a table, printing mechanism located in the middle of the table, a stencil track having an initial part extended from one end of the table through the printing mechanism and another part extended at right angles to the initial part and toward the rear of the table, means for advancing successive stencils along the first portion of said track through the printing mechanism, other means to advance the used stencils along the right angularly related portion of the track, an envelope 15 guideway extended parallel to the initial part of said stencil track, means for advancing successive envelopes to said printing mechanism along said guideway in a direction opposite to the line of advance of the stencils to said printing mechanism and means for advancing the addressed envelopes at right angles to their initial line of movement and toward the front of said table.

20 4. A stencil printing machine comprising a table, reciprocating printing mechanism located in the middle of the table, separate envelope and stencil holders disposed above the table on opposite sides of and in line with said printing mechanism, and separate stencil and envelope receivers located below the table and respectively at the rear and front thereof and into which the stencils and envelopes fall by gravity, separate guiding and advancing means to advance successive stencils in angularly-related paths from said stencil holder through said printing mechanism and into said stencil receiver, and separate guiding and advancing means to advance successive envelopes in separate ones of two angularly-related paths from said envelope holder through said printing mechanism and into the entrance of said envelope receiver.

25 5. A stencil printing machine including printing mechanism, a stencil track having two angularly related sections, means to advance successive stencils along one section of said track and through said printing mechanism to the entrance to the other section thereof, and means reciprocating lengthwise of said second portion of said track for engaging and advancing the stencils therealong, wherein means is provided that alternately moves said reciprocating stencil advancing means into and out of stencil engaging position.

30 6. A stencil printing machine including printing mechanism, a stencil track having two angularly-related sections, means to advance successive stencils along one section of said track and through said printing mechanism to the entrance to the other section thereof, means reciprocable lengthwise of said second section of said track for advancing the stencils therealong, and means

for holding said stencil advancing means out of engagement with a stencil during one part of the reciprocatory movement thereof and for moving it into position to engage a stencil during its reciprocatory movement in the opposite direction.

5 7. A stencil printing machine including a stencil track having angularly-related sections, means for moving successive stencils along one section of the track into the other section, and mechanism for advancing stencils along said other section comprising a member reciprocable lengthwise of said other section, a finger frame carried by said member overlying said other section and having fingers which are engageable with the successive stencils, and means for raising and lowering said finger frame in correspondence with reciprocatory movements thereof in opposite directions.

10 8. A stencil printing machine as defined in claim 7 wherein said frame raising and lowering means includes a pivoted frame which is engageable with said finger frame, and means including a cam that is rotated in timed relation with the reciprocatory movements of said finger frame for raising and lowering said pivoted frame.

15 9. A stencil printing machine comprising reciprocating printing mechanism adapted to operate upon successive stencils and envelopes when they are stationary in said mechanism, means for moving successive stencils intermittently through said printing mechanism and for leaving them momentarily stationary therein, guiding and advancing means for moving successive envelopes intermittently and independently of the stencil into the action of said printing mechanism and for leaving them momentarily stationary therein, and other means operable for moving the addressed envelopes out of said printing mechanism including guiding means for guiding the addressed envelopes to move at approximately right angles to their movement into the printing mechanism.

20 10. A stencil printing machine comprising reciprocating printing mechanism adapted to operate upon successive stencils and envelopes when they are stationary in said mechanism, separate mechanisms for moving successive stencils and envelopes intermittently and separately into the action of said printing mechanism and for leaving them momentarily stationary therein and including separate guideways which direct the stencils and envelopes into said printing mechanism, means for moving the addressed envelopes independently of the stencils away from the action of said printing mechanism and including a guideway along which the addressed envelopes are directed at approximately right angles to their movement into said printing mechanism.

25 11. A stencil printing machine comprising reciprocating mechanism, means for advancing stencils in successive order intermittently through and leaving them momentarily stationary in said printing mechanism during the printing operation, other means for advancing successive envelopes independently of the stencils into the action of said printing mechanism and for leaving them momentarily stationary therein during the printing operation, and means independent of said envelope advancing means and said stencil advancing means for removing the addressed envelopes from said printing mechanism.

30 12. A stencil printing machine comprising reciprocating printing mechanism, intermittently operative means for presenting successive sten-

cils to the action of said printing mechanism at times when the stencils are stationary, and means for presenting successive envelopes intermittently to the action of said printing mechanism at times 5 when the envelopes are stationary comprising an envelope holder, means for removing successive envelopes from said holder, intermittently operating means for engaging the removed envelopes and advancing them into the action of said printing 10 mechanism and for leaving them in stationary condition and other intermittently operating means for engaging the printed envelopes and removing them from the action of said printing mechanism independently of the stencils.

15 13. A stencil printing machine comprising printing mechanism, means for presenting successive stencils to the action of said printing mechanism, and means for presenting successive envelopes to the action of said printing mechanism comprising an envelope holder, means for removing successive envelopes from said holder, intermittently operating means for engaging the removed envelopes and advancing them into the action of said printing mechanism, a guideway 20 which directs the line of advance of the envelopes, and other intermittently operating means for engaging the printed envelopes and removing them from the action of said printing mechanism including a guideway angularly related to said first 25 guideway that directs the envelopes to advance in a direction that is different from the direction of advance of the unprinted envelopes toward said printing mechanism.

14. In a stencil printing machine having intermittently operating printing mechanism, and means for presenting successive stencils to the action of said printing mechanism, the combination therewith of means for presenting successive envelopes to the action of said printing mechanism and stencils comprising an envelope holder, a continuously rotating extractor drum for removing successive envelopes from said holder, intermittently operable feed rolls for engaging the removed stencils and for presenting them to 40 the action of said printing mechanism, other intermittently operable feed rolls for engaging the addressed envelopes and for removing them from the action of said printing mechanism, and means for operating said sets of feed rolls at times when 45 said printing mechanism is idle.

15. A stencil printing machine comprising reciprocating printing mechanism, a stencil track along which successive stencils are guided for movement into and out of the action of said printing mechanism, said track having two angularly-related straight portions, separate means for moving the stencils along different portions of said track at different times, and means for presenting a succession of envelopes to the action 50 of said printing mechanism at times when stencils are advancing along one portion of said track and are stationary in another portion thereof.

16. A stencil printing machine comprising printing mechanism, means for presenting successive stencils to the action of said printing mechanism, means for presenting successive envelopes to the action of said printing mechanism and stencils including a pair of cooperating 55 driving and idler rolls which are engageable with the successive envelopes to advance them into said printing mechanism, means including a cam which rotates in timed relation with the movement of said stencils for controlling the driving engagement of said driving and idler rolls

with the envelopes, other driving and idler rolls engageable with the addressed envelopes for removing them from the printing mechanism, and means including a cam operating in timed relation with said first named cam for controlling 5 the engagement of said last named driving and idler rolls with the addressed envelopes.

17. A stencil printing machine as defined in claim 16 wherein the rolls of both sets of driving and idler rolls are movable toward and away 10 from each other into and out of driving engagement with the envelopes, and wherein said cams control such movements.

18. A stencil printing machine comprising printing mechanism, means for presenting successive stencils to the action of said printing mechanism, means for presenting successive envelopes to the action of said printing mechanism and stencils including a pair of cooperating driving and idler rolls which are engageable 15 with the successive envelopes to advance them into said printing mechanism, means including a cam which rotates in timed relation with the movement of said stencils for controlling the driving engagement of said driving and idler rolls with the envelopes, other driving and idler rolls engageable with the addressed envelopes for removing them from the printing mechanism, and means including a cam operating 20 in timed relation with said first named cam for controlling the engagement of said last named driving and idler rolls with the addressed envelopes, said last named rolls being arranged to move the envelopes out of said printing mechanism in a direction that is different from the 25 direction of movement of the envelopes into said printing mechanism.

19. A stencil printing machine including printing mechanism, means to advance stencils intermittently to the action of said mechanism, 40 separate means to advance successive envelopes independently of the stencils in a step by step manner along separate ones of two angularly-related straight paths, angularly related guideways providing said paths, and printing mechanism having means for printing said envelopes 45 at times when they are stationary in one of said straight paths.

20. A stencil printing machine comprising reciprocating printing mechanism adapted to operate upon a succession of stencils and envelopes, separate means for advancing successive stencils and envelopes in different directions out of and away from said printing mechanism and separate means for simultaneously advancing successive envelopes and stencils in different directions toward and into said printing mechanism, and angularly related guideways for guiding the movements of said stencils and envelopes in said 50 different directions.

21. A stencil printing machine comprising reciprocating printing mechanism adapted to operate upon a succession of stencils and envelopes, separate means for advancing successive stencils into and out of said printing mechanism, 65 means for advancing successive envelopes into the action of said printing mechanism, and other means for removing the addressed envelopes from said printing mechanism, one of said envelope advancing means having means which when started in operation conditions one of said stencil advancing means for operation.

22. A stencil printing machine comprising reciprocating printing mechanism adapted to operate upon a succession of stencils and envelopes, 75

means for advancing successive stencils into said printing mechanism, means for removing successive stencils from said printing mechanism, and means for advancing successive envelopes toward said printing mechanism, said envelope advancing means having means for controlling the operation of said stencil removing means.

23. A stencil printing machine comprising a stencil track, printing mechanism disposed in operative relation with the stencils in said track, means for introducing successive stencils into said track, other means for advancing successive stencils along a portion of said track, and means including a reciprocating frame for advancing successive envelopes to the action of said printing mechanism, said reciprocating frame having means for controlling the operation of said stencil advancing means.

24. A stencil printing machine comprising a stencil track, printing mechanism disposed in cooperative relation with the stencils in said track, means for advancing a stencil along at least a portion of said track comprising a member capable of reciprocating lengthwise of said portion, a finger carried by said member movable into and out of engagement with the stencils in the track, and means for advancing successive envelopes towards said printing mechanism including a reciprocating envelope feed roll carrier which has means engageable with said stencil advancing finger for moving it into and out of stencil engaging position.

25. A stencil printing machine comprising a stencil track having a discharge section that is angularly related to the main portion of said track, printing mechanism disposed for cooperative relation with the stencils in the main portion of the track, means for advancing stencils along said angularly-related discharge section comprising a member capable of reciprocation lengthwise of said section, a finger frame pivotally carried by said reciprocatory member and disposed above said track section and having fingers which are engageable with the successive stencils in the track for advancing them along said section, means for advancing successive envelopes to the action of said printing mechanism comprising a feed roller which is adapted to engage the successive envelopes to advance them towards said printing mechanism, and a reciprocating frame which carries said feed roll and is reciprocable to move said feed roll into and out of envelope engaging position, said reciprocating frame having means which engages said finger frame and reciprocates it into and out of stencil engaging position concurrently with movements of said roll into and out of envelope engaging position.

26. A stencil printing machine comprising a stencil track having a discharge section that is angularly-related to the main portion of said track, printing mechanism disposed for cooperative relation with the stencils in the main portion of the track, means for advancing stencils along said angularly-related discharge section comprising a member capable of reciprocation lengthwise of said section, a finger frame pivotally carried by said reciprocatory member and disposed above said track section and having fingers which are engageable with the successive stencils in the track for advancing them along said section, means for advancing successive envelopes to the action of said printing mechanism comprising a feed roller which is adapted to engage the successive envelopes to advance them towards said printing mechanism, a reciprocating

frame which carries said feed roll and is reciprocable to move said feed roll into and out of envelope engaging position, said reciprocating frame having means which engages said finger frame and reciprocates it into and out of stencil engaging position concurrently with movements of said roll into and out of envelope engaging position, and means for reciprocating said reciprocating frame and said reciprocating member in timed relation.

27. A stencil printing machine comprising a stencil track, means for advancing stencils along said track, printing mechanism disposed for cooperative relation with the stencils in said track, and mechanism for presenting successive envelopes to the action of said printing mechanism and stencils comprising separate mechanisms operating in timed sequence and in timed relation to the operation of said printing mechanism for advancing said envelopes towards said printing mechanism and for removing the addressed envelopes away from said printing mechanism, one of said separate envelope advancing mechanisms having means which controls the operation of said stencil advancing means.

28. A printing machine comprising reciprocating printing elements, means for presenting successive envelopes to and for removing them from the action of said printing elements comprising an envelope holder, a drum engageable with the successive lowermost envelopes in said holder for advancing them therefrom, intermittently advancing and separating feed rolls disposed between said envelope holder and printing elements for advancing successive envelopes from said drum into the action of said printing elements, and other intermittently advancing and separating feed rolls disposed in front of said printing elements for moving the addressed envelopes away from the action of said printing elements at an angle to the direction of advance of the stencils of the envelopes thereto.

29. A printing machine comprising reciprocating printing elements, means for presenting successive envelopes to and for removing them from the action of said printing elements comprising an envelope holder, a drum engageable with the successive lowermost envelopes in said holder for advancing them therefrom, intermittently advancing and separating feed rolls disposed between said envelope holder and printing elements for advancing successive envelopes from said drum into the action of said printing elements, other intermittently advancing and separating feed rolls disposed in front of said printing elements for moving the addressed envelopes away from the action of said printing elements at an angle to the direction of advance of the stencils of the envelopes thereto, and cam means for advancing and separating said sets of feed rolls in timed sequence.

30. A stencil printing machine comprising printing mechanism, operating mechanism for said printing mechanism having a disengageable connection therewith, means for advancing a succession of stencils through said printing mechanism, means for advancing a succession of envelopes through said printing mechanism including a rotary feeding member which is engageable with the envelopes, a driving member for said rotary feeding member having a disengageable connection therewith, and electrical means under control of the stencils for separately but simultaneously disengaging said disengageable connections for disabling said printing mecha-

nism and the operation of said rotary feeding member.

31. A stencil printing machine comprising printing mechanism, operating mechanism therefor having a breakable connection therewith, means for advancing a succession of stencils through said printing mechanism, means for advancing a succession of envelopes through said printing mechanism including a rotary feed drum which is engageable with the envelopes to advance them, a drive shaft for said drum having a breakable connection therewith, and means controlled by the stencils for controlling the conditions of both of said breakable connections.

15 32. A stencil printing machine comprising printing mechanism, reciprocating means for advancing a succession of stencils intermittently through said printing mechanism, means for advancing a succession of envelopes through said printing mechanism including a rotary feed drum which is engageable with the successive envelopes, a feeding roll which is reciprocable toward and away from the envelopes advanced by said feed drum in timed relation with the advance of said 20 stencils for advancing the envelopes into the action of said printing mechanism, a drive shaft for said feed drum having a breakable connection therewith, and means under control of said stencils for making and breaking said breakable 25 connection.

30 33. A stencil printing machine comprising printing mechanism having disabling means, means for advancing a succession of stencils through said printing mechanism, means for advancing a succession of envelopes through said printing mechanism including a rotary feed drum which is engageable with the successive envelopes, a drive shaft for rotating said drum having a breakable connection therewith, means including an electromagnet controlling said breakable 35 connection, and selector mechanism controlled by said stencils for controlling both the energization of said electromagnet and the operation of said printing mechanism disabling means.

40 34. In a stencil printing machine having printing mechanism, means for advancing a succession of stencils through said printing mechanism, and selector mechanism controlled by said stencils for controlling the operation of said printing mechanism, the combination therewith of means for advancing a succession of envelopes through said printing mechanism, means including a plurality of electromagnets for controlling the operation of said envelope advancing means, 45 and means for energizing a selected one of either of said electromagnets under control of said selector mechanism.

45 35. In a stencil printing machine having printing mechanism, means for advancing a succession of stencils through said printing mechanism, selector mechanism controlled by said stencils for controlling the operation of said printing mechanism, the combination therewith of mechanism for advancing successive envelopes through said printing mechanism including an envelope feeding drum, a drive shaft therefor having a breakable connection therewith, a plurality of 50

electromagnets each independently operable to control said breakable connection and the energization of all of which is controlled by said selector mechanism, and means operable at will for selecting a particular one of all of said electromagnets for control by said selector mechanism.

5 36. In a stencil printing machine having printing mechanism, means for advancing a succession of stencils through said printing mechanism, and selector mechanism controlled by said stencils for controlling the operation of said printing mechanism, the combination therewith of mechanism for advancing successive envelopes through said printing mechanism comprising an envelope feeding drum, a drive shaft therefor having a breakable connection therewith, a control member for said breakable connection, a pair of electromagnets controlled by said selector mechanism arranged to move said control member in opposite directions when energized, and means operable at will for selecting a particular electromagnet for control by said selector mechanism.

10 37. In a stencil printing machine having printing mechanism, means for advancing a succession of stencils through said printing mechanism, selector mechanism controlled by said stencils for controlling the operation of said printing mechanism, the combination therewith of mechanism for advancing successive envelopes through said printing mechanism including an envelope feeding roll, a drive shaft therefor having a breakable connection therewith, a control member which is movable in one direction to make said connection and in the opposite direction to break said connection, a pivoted armature for reciprocating said control member, a control frame having an over-center spring which is movable across the pivot of said armature into opposite positions where it holds said armature yielding into a selected one of two opposite positions, electromagnets operating on said armature on opposite sides of the pivot thereof for actuating said armature, and means for selecting a particular one of said electromagnets for control by said selector mechanism.

15 38. In a stencil printing machine having printing mechanism, means for advancing a succession of stencils through said printing mechanism, selector mechanism controlled by said stencils for controlling the operation of said printing mechanism, mechanism for advancing a succession of envelopes through said printing mechanism including an envelope feeding drum, a drive shaft therefor having a breakable connection therewith, a control member movable in opposite directions to control the condition of said breakable connection, an armature movable in opposite directions for correspondingly moving said control, oppositely acting electromagnets cooperating separately with said armature to move it in opposite directions, and a frame having an overcenter spring engageable with said armature to hold it against a selected one of said electromagnets, and means for selecting a particular one of said electromagnets for control by said selector mechanism.

HARMON P. ELLIOTT.
